(57) **CLAIM**

The ornamental design for a side table as shown and described.

DESCRIPTION

FIG. 1 is a perspective view of a side table showing my new design;

FIG. 2 is a perspective view of the main body of the side table shown separately for ease of illustration;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of portion 10 shown in FIG. 3;

FIG. 11 is a perspective view of the socket assembly of the side table shown separately for ease of illustration;

FIG. 12 is another perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof; and,

FIG. 18 is a bottom plan view thereof.

The dash-dash broken lines in the drawings depict portions of the side table that form no part of the claimed design. The dot-dash broken lines in FIGS. 3 and 10 represent boundaries of the enlarged portions and form no part of the claimed design.

1 Claim, 18 Drawing Sheets
